Res. 776

Samuel H. Ransom, of Albany, N. Y.

Letters Patent, No. 776, Dated April 1, 1836.

The schedule referred to in these Letters Patent, and making part of the same.

To whom it may concern:

Be it known that I, Samuel H. Ransom of the City of Albany, in the State of New York, have produced a new and original ornamental Design for an Elevated Oven Cooking Stove, and I hereby declare that the annexed drawings are a full and accurate description and delineation of the ornamental parts with their several ornaments, the side plates and the end plates, not represented being precisely similar to and similarly ornamented with the side plates, and the end plate represented in the drawings.

What I claim as my production and desire to secure by Letters Patent, is the combination and arrangement of ornamental figures and forms, represented

2

Ms. T76

in the accompanying drawings, forming together an
ornamental Design for an Elevated (or Cooking)
Stove.
